U.S. Notice of Allowance dated Oct. 13, 2011, issued in U.S. Appl. No. 29/376,770.

Primary Examiner — Clare E Heflin*(74) Attorney, Agent, or Firm* — KED & Associates LLP**(57) CLAIM**

We claim the ornamental design for a LED lighting apparatus, as shown and described.

DESCRIPTION

FIG. 1 is a front perspective view of a LED lighting apparatus; FIG. 2 is a front view of the LED lighting apparatus of FIG. 1; FIG. 3 is a rear view of the LED lighting apparatus of FIG. 1; FIG. 4 is a left side view of the LED lighting apparatus of FIG. 1; FIG. 5 is a right side view of the LED lighting apparatus of FIG. 1; FIG. 6 is a top view of the LED lighting apparatus of FIG. 1; FIG. 7 is a bottom view of the LED lighting apparatus of FIG. 1; FIG. 8 is a front perspective view of the LED lighting apparatus of FIG. 1 shown in use installed on an exemplary ceiling with the light emitting part in diagonal line; and, FIG. 9 is a rear perspective, cross-sectional view of the LED lighting apparatus of FIG. 1, taken along line 9-9 of FIG. 1. The broken lines shown on the drawings depict environment only and form no part of the claimed design.
